WATER CLOSET

Fred G. Bushold, Lawrence, Mass.

Application January 2, 1935, Serial No. 50

7 Claims.

(Cl. 4—98)

This invention relates to flush bowl and seat of a water closet, and is intended primarily to overcome the public health nuisance and unsanitary conditions prevailing in women's public lavatories now in general use.

The invention is embodied in the improvements hereinafter described and claimed.

Of the accompanying drawing forming a part of this specification,—

10 Figure 1 is a top plan view of the flush bowl and its seat.

Figure 2 is a side view of the same.

Figure 3 is an end view looking toward the front end.

15 Figure 4 is a section on line 4—4 of Figure 3.

The same reference characters indicate the same parts in all of the figures.

The bowl includes a seat-supporting rear portion 12 and a basin portion 13 projecting forward from the rear portion; said portions are integral with each other and preferably made of porcelain.

A seat 14 of the bifurcated form shown by Figure 1 is connected by a hinge 15 with the inner 25 end of the rear portion 12.

The basin portion 13 is formed to extend between, and project forward from the legs of a user occupying the seat.

The bowl has a continuous substantially horizontal oblong receiving mouth defining its upper margin, said mouth including the portions 120 and 130, and preferably the inwardly curved intermediate portions 131 located under and projecting forward from the forward ends of the seat 14, as shown by Figure 1. The object of said curved portions, which are extended downward to the base of the bowl, is to accommodate the lower portions of the legs of a user occupying the seat.

40 The wall of the bowl has a continuous internal surface converging inwardly and downwardly from the receiving mouth to an outlet 17 common to the bowl portions 12 and 13. The receiving area of the basin portion 13 is such that

45 said portion is adapted to receive urine projected forward from a point between the ends of the seat 14, and matter such as gargle liquid, saliva or vomitus, projected downward from the mouth of a user occupying the seat, without permitting 50 contact of such projected matter with the user's legs and clothing, and without liability of the escape of any such matter outside the bowl.

The maximum internal width of the basin portion 13 on the line 1—1, Figure 1 within the 55 mouth portion 130, is preferably about ten inches.

The maximum projection of the basin portion from a line 2—2 extending between the ends of the seat 14, indicated by the line 3—3, is preferably about twelve inches. The location of the natural position of a user's mouth in the space above the basin portion is approximately as indicated by the circle 4, this location ensuring the downward projection of matter discharged from the user's mouth, into the center of the basin portion.

5 The distance between the ends of the seat 14 is preferably approximately eight inches, this distance or spacing and the elevation of the seat above the bowl being such as to prevent liability of contact of any vital organ of the user's body 15 with either the seat or the bowl.

The maximum internal length of the rear portion 12 on the line 5—5 is preferably approximately twelve inches.

The bowl is provided with any suitable attaching base 18, and may be provided with any suitable vent such as that shown by Figure 4.

The described bowl and seat improvements have been invented by me to overcome a vicious public health nuisance and to alleviate an unsanitary condition in women's public lavatories. There has been a crying need for this reform for years, and my improvements fill such want.

The improved structure is absolutely safe and sanitary, because while seated on bowl no part 30 of a woman's vital organs comes in contact either with bowl or seat.

Women are afraid of contamination and contagion from the old bowl, and they have reason for this fear when using all structures heretofore provided. The result is, that no woman will sit on the old type of bowl and use it normally. They either stand on the seat or stand up and straddle the bowl to use it, with the result of spilled urine on seat, bowl, floor and their clothes. 40 This goes on all day long in public lavatories and results in a public health nuisance and an unsanitary condition of lavatories.

45 This may all be eliminated by installing my improved structure in public female lavatories. A woman can use my bowl safely, and in comfort, both physically and mentally.

Salient features of my improved structure:

1. It is a public health remedy.

2. The ends of the seat are separated in front approximately eight inches to prevent contagion.

3. The length and width of the bowl are such that it absolutely prevent spilling of urine on a floor.

4. The projecting basin portion of the bowl is large and wide enough to use as a vomitus and gargle receptacle, or spitoon. It allows one to sit on bowl and vomit in comfort without spilling 5 on floor or using urine and hand basins.

I claim:

1. A sanitary water closet including a rear evacuating portion, and a basin portion projecting forward therefrom; combined with a bifurcated seat mounted in position to support a person over said rear portion; said basin portion being formed to extend between and project forward from the legs of a user, said bowl having a continuous substantially horizontal oblong receiving mouth defining the upper margin of both portions, the seat being substantially co-extensive with the margin of said rear portion; the basin portion being formed to receive urine projected forwardly from a point between the ends of the seat, and matter projected downwardly from the mouth of a user, without permitting contact of such projected matter with the occupant's legs and clothing, and escape thereof outside the bowl.
2. A sanitary water closet as specified by claim 1, the longer sides of the oblong bowl having inwardly curved portions accommodating the lower portions of a user's legs, and located under the forward ends of the bifurcated seat.
3. A sanitary water closet as specified by claim 1, the longer sides of the oblong bowl having inwardly curved portions accommodating the lower portions of a user's legs, and located under the forward ends of the bifurcated seat, said ends being spaced apart to prevent contact of vital

organs of a user's body with either the bowl or the seat.

4. A water closet structure comprising a receiving bowl including a rear portion, and a basin portion projecting forward from the rear portion, in combination with a forked seat mounted in position to support a person over said rear portion; the basin portion being formed to extend between the legs of an occupant of the seat, said basin portion being located in position to receive discharges from two portions of the occupant's body, including the mouth, and formed to prevent the accidental escape of either discharge. 5

10 15 20 25 30 35

5. A water closet structure as specified by claim 4, the bowl having a receiving mouth common to the rear and basin portions thereof, the portion of said mouth associated with the basin portion, being extended outward from the center thereof sufficiently to prevent the accidental escape of matter discharged into the basin portion.

6. A water closet structure as specified by claim 4, the bowl being oblong and its longer sides recessed at the junction of the rear and basin portions to accommodate the legs of an occupant of the seat.

30 35

7. A water closet structure as specified by claim 4, the bowl being oblong and its longer sides recessed at the junction of the rear and basin portions to accommodate the legs of an occupant of the seat, the forward ends of the bifurcated seat being located immediately above said recessed sides, and spaced apart to prevent contact of a vital part of the occupant's body with either the bowl or the seat.

FRED G. BUSHOLD.
